T. SMITH

COMPOSITION OF MATTER AND METHOD OF MAKING THE SAME

Filed Dec. 9, 1925

UNITED STATES PATENT OFFICE.

THEODORE SMITH, OF NEW YORK, N. Y.

COMPOSITION OF MATTER AND METHOD OF MAKING THE SAME.

Application filed December 9, 1925. Serial No. 74,237.

This invention relates to compositions of matter and methods of making the same, and more particularly to an improved inlay product, in which the alternate metal and wood layers extend co-extensively through their entire surfaces.

The invention consists in having the metal and wood layers of the inlay composition of substantially the same texture, degree of hardness, and other workable characteristics, so that after these metal and wood members have been joined together in the rough, by glue, dowel pins, etc., and pressed tightly together so as to form substantially one single piece, though composed of different substances, it can be worked by the use of the saw, cutter or other tools, and by the emery cloth wheel or other polishing devices, as if it was all one integral piece of the same material throughout. The selection of the metal is such as to conform to the wood as near as possible. With a soft wood a correspondingly soft metal is used, and with a harder wood a correspondingly harder metal is used. In all cases, the metal extends throughout the wood. With these essential features, the metal and wood of substantially the same texture is glued and pressed together, with the metal and wood extending throughout in substantial parallelism or concentricity, whereby both surfaces can be turned or worked, in such where both sides or upper and lower surfaces are visible.

The invention differs from prior known inlays, in which the metallic inlay is inserted in grooves and pinned or riveted to the wood, and then filed flush with the adjacent wood, which is not only expensive, but unsatisfactory in that when the wood dries out, the pins or rivets become loose and the inlaid strips come out. Where the thinner strips of metal are glued on, the glue dries out. This known method of inlaying is done after the article is shaped and finished, and is usually done by metalworkers. My improvement has the distinction and marked difference over the foregoing in that instead of the metal being a surface inlay, it extends throughout the adjacent wood, and is turned, worked and finished throughout simultaneously with the adjacent wood. Furthermore, by the selection of metal and wood of the same working characteristics, the product is one which in respect to workability

is the same as if made entirely of that metal or entirely of that wood. As in nature, articles of different elements are composed of elements of different toughness and consequent workability, but by having been compacted in their separated state, form a matter of substantial workability of the same degree throughout, so by compacting metal and wood, each of the same workability, with each extending throughout the volume of the composite article, a new composition of matter with metal inlay is formed, which enables forming by sawing, cutting tools and finishing wheels, as if the article was of substantially the same constituency and consistency throughout. Thereby the inlay process is done away with and a great saving is effected.

It does not do to take any metal, because for instance, hard sheet metal such as German silver or nickel would be too tough relatively, and the tools would work through the wood and leave the sheet metal, and this would ruin the emery cloth and polishing wheel. On the other hand, to use tin foil or very soft metal would cause the tools to work through the tin foil, and leave the wood protrude. Moreover, if hard sheet metal such as German silver, nickel, silver, or brass, or any other metal of similar hardness be used, a certain saw would be required different from that used for the wood. And in turning, a different tool as used on wood would be required than that used for the hard metal. Such different tools would cut unevenly and rip the wood as it is the softer of the two. Besides the glue would not stand the strain of the tools and the object would be ripped apart. In my improvement the same saw or cutting tool can be used and the sandpaper or emery cloth wheel would not be affected, as would be the case if hard metal were used. When tin foil is used it is too soft, and besides would not give an even inlay effect, nor be able to take a high polish at its edge portions appearing along the wood.

In the present invention, a metal such as white metal is utilized which is of the same workability as the wood which is selected, and then the white metal and wood, when joined together by pressure, and worked, will offer the same resistance to the cutting tool and to the finishing tool.

The softer woods as poplar, dogwood, maple and beech, are joined with softer white metal compositions, and the harder woods as ebony, walnut, mahogany, snake, etc., are joined to white metal having a composition substantially that of these degrees of hardness. The composition of white metal is readily determined by varying its constituents, and the degree of hardness or softness thereby fixed. It is thus readily possible to produce a composite article of wood and metal of substantially the same workability throughout.

Another feature of my invention resides in the characteristic that if any portion of the wood adjacent the metal inlay is not smooth, or is slightly notched, then the metal on being pressed together with the wood, fills in these slight notches or unevennesses. This is particularly the case where the softer metal is used, though also the case where harder metal and wood is used, since a very heavy pressure is used in order to compact the wood and metal together. In certain cases, heat and pressure, serve to compact the layers of wood and metal.

The invention will be more fully described hereinafter, embodiments thereof shown in the drawings and finally pointed out in the claims.

In the accompanying drawings, Figure 1 is a plan view of one embodiment of my invention.

Figure 2 is a section on line 2—2 of Figure 1.

Figure 3 is a plan view of another embodiment.

Figure 4 is a section on line 4—4 of Figure 3.

Figure 5 is a plan of another embodiment.

Figure 6 is plan of another embodiment.

Figure 7 is another embodiment, and

Figure 8 still another embodiment.

Similar characters of reference indicate corresponding parts.

Referring to the drawings, and more particularly to Figures 3 and 4, a layer of wood 10 alternates with a layer of metal 11. These are arranged parallel with each other, and extend through from top surface 12 to the lower surface 13.

In Figures 1 and 2, parallel layers, and diagonally arranged layers 14 are provided intermediate suitably shaped blocks of wood 15.

In Figure 5, the wood is composed of two sections 16 and 17, and has circularly shaped slots extending through the entire thickness of the wood, and in these slots the correspondingly curved metal inlay 16^a is placed which extends throughout the thickness of the wood from top to bottom surface. Joinders 17^a indicate where the wood joins, no metal being therebetween.

In Figure 6, other curved metal inlays 18

with a central circular inlay 19, are provided which extends from the top to the bottom of the layer of wood which has been provided first with these slots of the depth throughout the thickness of the wood. Other configurations come within the scope of my invention.

In Figure 7, an embodiment is shown in which upper and lower surfaces are not flat, but only one exposed surface is shown, in which the metal is indicated by 20 and the wood by 21. This form is suitable for umbrella or cane handles.

In Figure 8, a series of circular metal inlays are shown, indicated by 25 with wood 26 without and inserts 27 within.

In each of the foregoing cases, the wood which is utilized with the metal therebetween, are so selected as to be of the same workability throughout. They are worked and finished together. The metal and wood extend throughout their respective volumes.

Thus, rough edged pieces of wood may be joined with irregularly shaped pieces of metal, and then the cutting tool cuts down this composition of matter to the approximately final shape desired, and this is then finished or polished, as if all of one piece of either metal or wood.

In each of the above cases or embodiments, the selected metal and selected wood, is joined together by gluing preferably, and then by intense compacting pressure, applied in a manner in parallelism with the contacting surfaces of the wood and metal, so as to make these two substances as if one, they being of substantially the same texture, hardness, and workability.

The inlay extends from one surface to the diametrically opposite surfaces to be able to provide both surfaces to be finished alike of polished form, as in the case of humidor covers, fancy boxes, bookends, smoker sets, etc., where both sides are seen.

The inlay may be given any design. When the inlay has the necessary width, it may be engraved, or the wood and metal may be carved.

The finish may be either polished or buffed, and in either case the metal is selected accordingly. Also where stains for the wood are used, the metal is accordingly selected, so that the greasy metal does not take the stain.

The inlay composition of matter may be used for many purposes, as humidor, cigarette cases, fancy boxes, cane or umbrella handles, brush backs, pipes, furniture (wood trim), flooring trim, etc.

The essential feature of my invention is to have the metal inlay of substantially the same texture, degree of hardness or softness, and workability as that of the wood, with the wood and metal compacted together by pres-

sure, and the metal and wood layers coextensive throughout the volume of the article, with the constituent parts thereof worked out and finished simultaneously, as if only one substance was present.

In certain cases instead of using wood, pyralin of different consistency may be selected, and in other cases instead of using white metal, aluminum of suitable consistency may be selected. Either or both opposed surfaces may be finished, and when so finished and polished the metal takes on a high polish, except in such cases where a dull or buff finish is desired. If only one surface is desired to be finished it is sufficient to have the metal extend only one-half ($\frac{1}{2}$) way through approximately, that is not entirely through, though this is preferable.

In case white metal is used which is an alloy of tin, copper and antimony, for the harder kinds of wood about 85% of tin is used, for the softer kinds of wood about 95% of tin is used, with variations of the tin contents for woods intermediate these harder and softer woods, and with variations of copper and antimony proportionately to the tin contents and to the degree of hardness or softness of the wood. Aluminum may be alloyed with copper and zinc, and variations of aluminum or copper or zinc determined by the hardness or softness of such an alloy.

I have described and shown various embodiments of my invention but it is clear that changes may be made without departing from the spirit of my invention as defined in the appended claims.

I claim as new:

1. An inlay composition of matter, consisting of separated soft metal and wood, said metal being alloyed to substantially the particular degree of hardness of the wood, whereby the wood and metal are of substantially the same tool resisting workability under the action of the cutting and finishing tools, with the soft metal and wood extending substantially throughout the volume of the article so formed and compacted together under the action of pressure to form one piece of substantially the same tool resisting workability throughout with the exposed surfaces of wood and soft metal equally finished, by virtue of their same tool resisting workability.

2. The method of making inlay composition of matter which consists in joining with wood soft metal of substantially the same degree of hardness, texture and tool resisting workability as that of the wood, gluing the layers of wood and metal together, subjecting the same to high pressure to compact the layers of soft metal and wood together in substantially one piece, and then working the exposed surfaces of the wood and metal of the composite structure to approximate shape, and finally finishing the surfaces of the wood and metal, both wood and metal simultaneously, and co-extensively by reason of their same tool resisting workability.

In testimony that I claim the foregoing as my invention, I have signed my name hereto.

THEODORE SMITH.
